The ornamental design for a display for a tire pressure monitoring system, as shown and described.

DESCRIPTION

FIG. 1 is a front elevational view of a display for a tire pressure monitoring system showing my new design, in an unenergized state, according to an embodiment of the invention;

FIG. 2 is a front elevational view of a display for a tire pressure monitoring system showing my new design, in an unenergized state, according to another embodiment of the invention;

FIG. 3 is a front elevational view of the display for a tire pressure monitoring system of FIG. 1, in an energized state showing exemplary values of the front and rear tire pressures and exemplary graphical indicators therefor, according to an embodiment of the invention; and,

FIG. 4 is a front elevational view of the display for a tire pressure monitoring system of FIG. 1, depicted in the environment of an exemplary tire pressure monitoring system, in an energized state showing alternate exemplary values of the front and the rear tire pressures and exemplary graphical indicators therefor, according to an embodiment of the invention.

The other views are flat and do not contain ornamentality and thus have been omitted. The matter shown in dashed lines is environmental structure and forms no part of the claimed design.
